DESIGN FOR AN ANIMAL FIGURE

Irving Miller, New York, N. Y.

Application August 18, 1948, Serial No. 148,173

Term of patent 14 years

(Cl. D34—2)

To all whom it may concern:

Be it known that I, Irving Miller, a citizen of the United States of America, residing in the Borough of Queens, city of New York, county of Queens, and State of New York, have invented a new, original, and ornamental Design for an Animal Figure, of which the following is a specification, reference being had to the accompanying drawing, forming part thereof:

I claim:

The ornamental design for an animal figure, as shown.

IRVING MILLER.
